UNITED STATES PATENT OFFICE.

WALTER S. NATHAN, OF MILWAUKEE, WISCONSIN.

LAMP-POSITION CONTROLLER.

1,416,376.

Specification of Letters Patent. Patented May 16, 1922.

Application filed June 28, 1920. Serial No. 392,170.

To all whom it may concern:

Be it known that I, WALTER S. NATHAN, a citizen of the United States, residing at Milwaukee, in the county of Milwaukee and 5 State of Wisconsin, have invented new and useful Improvements in Lamp-Position Controllers, of which the following is a specification.

This invention relates to a lamp position 10 controller.

It is particularly applicable to lamps or spot lights to control the movements thereof in a plurality of planes. One such application is to lamps of the Stewart Warner 15 type, but it is not limited to such use.

One of the objects of this invention is to provide means for limiting the movement of a lamp or spot light to confine the reflected rays within a pre-determined area.

20 Another object is to provide means adapted to be applied as a unit to a spot light in common use, without requiring extensive alterations, for limiting the vertical movement of the lamp within a pre-determined 25 angle of a horizontal plane.

Another object is to provide a simple attachment of few parts adapted to be applied to a lamp to limit the movement thereof to confine the rays within a given zone 30 when projected forward of the vehicle so as 35 to eliminate objectionable glare.

Another object is to provide means to limit the vertical movement of a lamp when in road illuminating position, but to permit 40 unlimited movement of the lamp for other 45 positions.

A further object is to provide means particularly adapted to be applied to a Stewart Warner lamp to so control the movements 50 thereof as to prevent objectionable glare to pedestrians, and occupants of approaching vehicles.

Other objects and advantages will herein- 55 after appear.

The lamp position controller has the following advantages:

It forms a unit which is both compact and of few parts.

It may be readily applied to lamps already 55 in use.

It can be attached to the lamp so as not to be readily visible, thus aiding its efficacy and not detracting from the pleasing appearance of the lamp.

It may be readily and economically manu- 55 factured.

No extensive alterations need be made in the lamp when attaching the position controller.

An embodiment of the invention is illus- 60 trated in the accompanying drawings, in which

Fig. 1 is a front elevation, partly in section, of a spot light support with the lamp in road illuminating position;

Fig. 2 is a developed elevation on the line 2-2 of Fig. 1, showing the lamp position controller adjusted to restrict the vertical movement of the lamp;

Fig. 3 is a view similar to Fig. 2, showing 70 the lamp position controller adjusted to permit unrestricted vertical movement of the lamp in non road illuminating position;

Fig. 4 is a perspective of the lamp position controller;

Fig. 5 is a side elevation, partly in section, of the lamp and support, on the line 5-5 of Fig. 1; and

Fig. 6 is a broken section of the end of the yoke and the lamp casing.

The invention in general comprises a lamp controlling means including a cam or notched member movable with the lamp in one plane, another cam or notched member movable with the lamp support and means co-operating with said members to determine the movement of the lamp under pre-determined conditions to limit the movement of the lamp in a vertical plane when the lamp is in a road illuminating position.

A lamp or spot light 1 is rotatably mounted on a yoke 2, which is preferably pivotally mounted on a suitable bracket arm 3. The bracket 3 may be mounted on any suitable standard 4 such, for example, as one of the 95 uprights for the wind shield.

The lamp 1 may be moved in a vertical plane about its horizontal axle of support, and may be bodily moved in a horizontal plane about the vertical supporting axis of 100 the yoke 2.

It is desirable that the movement of the lamp in a vertical plane be limited when the lamp is moving through such an angle of a horizontal plane as to occupy road illuminating position. This angle may be thirty degrees on either side of the direction of travel. The vertical movement of the lamp should preferably be so restricted that the glaring rays of light will not be projected forward 110 of the vehicle more than a certain distance, such, for example, as 40 to 70 feet.

When the lamp is out of road illuminating position there is no possibility of the rays of light therefrom being projected into the eyes of the occupants of approaching vehicles, and its vertical movement should be unrestricted to permit the proper illumination of objects along the side of the road.

The movements of the lamp 1 may be controlled by providing a cam or notched member 5, movable with the lamp, another cam or notched member 6, movable with the yoke 2, and an intermediate stop or control link 7 operatively associated with the cams 5 and 6. The functioning position of the link 7 is dependent upon the relative position of the two cams, or in other words, upon the relative position of the lamp and yoke. The construction and relative arrangement of the cams 5, 6 and the link 7 should be such that within a pre-determined angle of a horizontal plane, the movement of the lamp in a vertical plane is restricted.

The cam 5 is suitably mounted on the casing of the lamp as by rivets 9 (see Fig. 6), but any other suitable means may be provided for mounting the cam 5 so that the movements thereof will correspond with those of the lamp 1. The lamp 1 is rotatively supported in the yoke 2 by means of screws or rivets 10. A nut 11 co-operates with each screw or rivet to hold the parts in proper relation.

The cam 6 is attached to the yoke 2 by rivets 12. The yoke 2 is rotatably mounted 35 on the bracket 3 by a stud 13. The threaded end of the stud shank engages the cam 6, and a washer 14 co-operates therewith to hold the bracket 3 and the yoke 2 in spaced relation. Other means may, of course, be 40 employed for attaching the cam 6 to the yoke 2 so that the two may move together.

The control link 7 is mounted on the yoke 2 and is preferably formed of wire, rod or other suitable material of sufficient stiffness 45 to resist bending under compression. The yoke 2 carries guides 8 for the link 7. One end of the link 7 is maintained in engagement with the cam 6 by means of a coiled spring 16 encircling the link 7. One end of the spring is fastened to the link and the other is seated against the guide 8.

For the purpose of reducing the friction between the link 7 and the cam 5, a roller 17 is mounted on the end of the link 7.

55 For the purpose of restricting the movement of the lamp 1 in a vertical plane, when the lamp is moved through a certain angle of a horizontal plane, the respective cams 5 and 6 are provided with suitable co-operating raised or notched portions. The cam 6 is provided with a raised portion 18 which prevents the movement of the link 7, while the yoke 2 is being moved through a certain angle in a horizontal plane. The cam 5 60 is provided with a raised portion 19, the

ends 20 of which form stops for the roller 17, and limit the movement of the lamp in a vertical plane, as long as the raised portion 18 of the cam 6 is in a position to limit the movement of the link 7, as shown in Fig. 2.

Fig. 3 shows the relative position of the parts for all other positions of the cam 6, which positions correspond to an extended movement of the lamp in a horizontal plane, such, for example, as when the lamp is turned to illuminate a sign at the side of the road. The lamp then has an unrestricted movement in a vertical plane. In the latter position, the yieldingly pressed link 7 is free to move so that the end 15 thereof may ride upon the raised cam surface 19. As long as the end of the link engages the raised portion 19 of the cam 5, the lamp is prevented from being turned to a road illuminating position, because the opposite end 21 of the link would strike one of the shoulders 22 of the cam 6. In order to again move the lamp to a road illuminating position, it must be moved to a position within the restricted vertical movement when the roller 17 again rests on the depressed portion of the cam 5.

The invention contained herein is of course susceptible of other embodiments and adaptations.

I claim—

1. In combination with a movably mounted support and a lamp mounted for movement on said support, lamp positioning means comprising a cam adapted to move with the support, another cam adapted to move with the lamp, and means dependent upon the relative position of the cams for determining the movement of the lamp. 100

2. A lamp position controller for a lamp pivotally supported on a horizontal axis in a yoke pivotally supported to move in a horizontal plane, comprising a cam fixed to the lamp, a cam fixed to the yoke, a rod extending between and in operative relation to the cams, and a spring holding one end of the rod in engagement with the cam fixed to the lamp. 110

3. A lamp position controller for a lamp pivotally supported on a horizontal axis in a yoke pivotally supported to move in a horizontal plane, comprising a cam fastened to the lamp, a cam fastened to the yoke, a spring, and a rod forced against the action of the spring into the path of the yoke cam by the lamp cam. 115

4. A lamp position controller for a lamp pivotally supported on a horizontal axis in a yoke pivotally supported to move in a horizontal plane, comprising a pair of cams each having a raised portion on the periphery thereof, one cam being fixed to the lamp and the other to the yoke, and a spring pressed rod one end of which is held in engagement 120

125

130

with the lamp cam and the other end of which is forced into the path of the raised portion of the yoke cam by the raised portion of the lamp cam.

- 5 5. The combination of a yoke mounted for movement in a horizontal plane, a lamp rotatably mounted in the yoke for movement in a vertical plane, a cam fixed to the lamp, a cam fixed to the yoke, each cam having a raised portion on the periphery thereof, and a rod having one end yieldingly engaging one of the cams and the other end thereof forced by the raised portion of one cam into the path of the raised portion of the other cam.
- 10 6. The combination of a yoke supported for movement in a horizontal plane, lamp mounted in the yoke for movement in a vertical plane, and means dependent upon the position of the yoke in the horizontal plane for determining the limits of movement of the lamp in the vertical plane, said means comprising a cam fastened to the yoke and a cam fastened to the lamp, said cams having notched peripheries; and a rod positioned between the peripheries of the cams,
- 15
- 20
- 25

one end of the rod being moved into the path of the notched periphery of the yoke cam by the notched periphery of the lamp cam.

30 7. In combination with a lamp and a support therefor, means co-operating with the lamp to limit the movement thereof in a vertical plane when in a predetermined horizontal position, said means comprising a 35 notched member movable with the lamp, a spring pressed member normally engaging the notched member, and a stop associated with the support and cooperating with the spring pressed and notched members to 40 determine the movement of the lamp.

8. A lamp position controller comprising relatively movable members mounted at spaced points to rotate about different axes, and means cooperating with the two members and dependent upon the relative position thereof for limiting the movement of one of the members.

In witness whereof, I have hereunto subscribed my name.

WALTER S. NATHAN.
